US00D832218S

(12) **United States Design Patent** (10) **Patent No.:** **US D832,218 S**
Wronski et al. (45) **Date of Patent:** **** Oct. 30, 2018**

(54) **JUNCTION BOX FOR REGRESSED LIGHT ENGINE**

(71) Applicant: **Cooper Technologies Company**, Houston, TX (US)

(72) Inventors: **Grzegorz Wronski**, Peachtree City, GA (US); **Steven Walter Pyshos**, Peachtree City, GA (US); **Oliver Ernst**, Peachtree City, GA (US); **Rongxiu Huang**, Shanghai (CN)

(73) Assignee: **Cooper Technologies Company**, Houston, TX (US)

(**) Term: **15 Years**

(21) Appl. No.: **29/617,946**

(22) Filed: **Sep. 18, 2017**

(51) LOC (11) Cl. **13-03**
(52) U.S. Cl. **USPC D13/152**

(58) **Field of Classification Search**

USPC ..... D13/152, 119, 147, 156, 177, 184, 107, D13/108, 110, 123, 133, 137.1–137.4, D13/138.1–138.2, 139.1–139.8, 153, 154, D13/146, 158; D8/350, 351–353; D25/119, 127, 134, 48.4; D26/74, 138 CPC F21S 8/02; F21V 23/00; F21V 23/001; H01R 25/00; H01R 25/006; H01R 11/00; H01R 9/00; F16J 13/10; F16B 5/02

(57) **CLAIM**

The ornamental design for a junction box for regressed light engine, as shown and described.

DESCRIPTION

FIG. 1 is a top perspective view of a junction box for regressed light engine, showing our new design;

FIG. 2 is a first side view thereof;

FIG. 3 is a second side view thereof;

FIG. 4 is a third side view thereof;

FIG. 5 is a fourth side view thereof;

FIG. 6 is a top plan view thereof;

FIG. 7 is a bottom plan view thereof; and,

FIG. 8 is a bottom perspective view thereof.

The broken lines shown in the figures illustrate portions of the junction box for regressed light engine that form no part of the claimed design.

1 Claim, 8 Drawing Sheets
